Primary Examiner — Bridget L Eland(74) *Attorney, Agent, or Firm* — Kenja IP Law PC(57) **CLAIM**

The ornamental design for an electronic device, as shown and described.

DESCRIPTION

FIG. 1 is a front perspective view of an electronic device showing my new design;

FIG. 2 is a rear perspective view thereof;

FIG. 3 is a front view thereof;

FIG. 4 is a rear view thereof;

FIG. 5 is a top plan view thereof;

FIG. 6 is a bottom view thereof;

FIG. 7 is a right side view thereof;

FIG. 8 is a left side view thereof; and,

FIG. 9 is a partial cross-sectional view taken along line 9-9 in FIG. 4 of the portion defined by 9'-9' in FIG. 4.

The dashed broken lines in FIG. 4 are used to identify cross-sectional view and form no part of the claimed design. The dashed broken lines in FIG. 9 are directed to environment and form no part of the claimed design.

1 Claim, 9 Drawing Sheets(56)
